UNITED STATES PATENT OFFICE.

JOHN C. PAIGE, OF STONEHAM, MASSACHUSETTS, ASSIGNOR OF ONE-HALF TO GEORGE A. OSGOOD, OF SAME PLACE.

DAMPER-REGULATOR.

SPECIFICATION forming part of Letters Patent No. 324,270, dated August 11, 1885.

Application filed June 1, 1885. (No model.)

To all whom it may concern:

Be it known that I, JOHN C. PAIGE, of Stoneham, in the county of Middlesex and State of Massachusetts, have invented certain new and useful Improvements in Damper-Regulators, of which the following is a specification.

This invention relates to appliances operated by variations of pressure in a steam-boiler to move a damper in a flue from the furnace which generates the steam to the chimney thereof, so that when the pressure rises above or falls below a given point the draft is checked or increased, as the case may be.

The object of the invention is to provide a simple, durable, and compact apparatus of this class; and it consists in the several improvements which I will now proceed to describe.

Of the accompanying drawings, forming a part of this specification, Figure 1 represents a front view of a boiler, its casing or setting, and a part of the chimney in connection with my improved regulator. Fig. 2 represents a vertical section of the regulator.

25 The same letters of reference indicate the same parts in all the figures.

a represents a casing composed of two parts or sections bolted together and having a chamber or space, b, between them which communicates through a pipe, c, with the lower portion of the steam-boiler, the casing having a passage, b', screw-threaded at its outer end, into which the pipe c is screwed. The chamber b is circular in horizontal section and contains a circular piston, e, which has a limited vertical play in the chamber. The periphery of the piston is separated from the surrounding surface of the chamber by an annular space into which is inserted a packing ring or 35 rings, f, of rubber, each ring being composed of a cylindrical piece of rubber, so that it serves both as a packing-ring and as an annular roller permitting the free vertical play of the piston.

45 On the upper side of the piston is a central boss, e', which projects into a guiding-opening, g, in the top of the casing.

h represents a lever bearing upon a link, i, which is supported by the boss e'. Said lever 50 is provided at one end with an aperture which

receives a knife-edged stud, j, affixed to ears k on the casing, said stud constituting the fulcrum of the lever and being in close proximity to the link i. The outer end of the lever h has an adjustable weight, m.

55

n represents a second lever fulcrumed at one end on a knife-edged stud, o, attached to ears p on the casing.

r represents a link interposed between the levers h n, and supporting the lever n at a point near its fulcrum. The lever n has an adjustable weight, s, and is extended a sufficient distance to enable it to give motion through a rod, t, to a crank, u, on the axis of a damper, v, in the flue leading from the furnace or boiler- 65 casing to the chimney.

The operation is as follows: The pressure in the boiler is communicated through the pipe c to the piston e, and either raises said piston or allows it to be depressed by the weighted levers; accordingly as the pressure increases or diminishes. When the piston is raised, the outer ends of the levers h n are raised by it, and the lever n is caused to partially close the damper, thus checking the fire and preventing further increase of steam-pressure. When the piston falls, the damper is opened and the heat of the fire increased. The rolling packing-rings prevent the water or steam that actuates the piston from passing the piston, the rolling motion of the rings preventing them from being worn or chafed by the movements of the piston.

It will be observed that the fulcrums of the levers h n are at opposite sides of the center of the casing, and that said levers project in opposite directions, so that they counterbalance each other, and therefore have no tendency to tip the casing in either direction. This arrangement enables the casing and the entire apparatus to be made in compact form, and also enables the casing to be easily secured to its support.

I claim—

1. In a damper-regulator, the combination of the casing having the chamber or space b, adapted to be connected with a steam-boiler, the piston adapted to move in said casing, the rolling packing ring or rings interposed between said piston and the surrounding surface 95 100

of the chamber, and the damper-operating devices supported by the piston, as set forth.

2. The combination of the casing having the chamber or space *b*, adapted to be connected with a steam-boiler, the piston in said chamber having a central boss projecting into an opening in the casing, the levers *h n*, fulcrumed at opposite sides of the center of the casing and extending in opposite directions across

10 the casing, as shown, whereby the apparatus

is counterbalanced, and the links *i r*, supporting the levers, as set forth.

In testimony whereof I have signed my name to this specification, in the presence of two subscribing witnesses, this 27th day of 15 May, 1885.

JOHN C. PAIGE.
